DESIGN FOR A COMBINED PITCHER AND COVER THEREFOR

Ralph E. Kruck, Springfield, Mass., assignor to
Westinghouse Electric & Manufacturing Com-
pany, a corporation of Pennsylvania

Application January 10, 1939, Serial No. 82,270

Term of patent 7 years

To all whom it may concern:

Be it known that I, Ralph E. Kruck, a citizen
of the United States, residing at Springfield, in
the county of Hampden and State of Massachu-
setts, have invented a new, original, and orna-
mental Design for a Combined Pitcher and Cover
Therefor, of which the following is a specification,
reference being had to the accompanying draw-
ing, forming a part thereof.

Fig. 1 is a side view of the combined pitcher and
cover therefor showing my design.

Figures 2, 3 and 4 are front, rear and top plan
views, respectively, of the design shown in Fig. 1.

I claim:

The ornamental design for a combined pitcher
and cover therefor as shown.

RALPH E. KRUCK.
